UNITED STATES PATENT OFFICE.

WILLIAM A. MATHEWS, OF GRATIS, OHIO.

DESIGN FOR A BODY OR BACK FOR PENCIL-CASES.

SPECIFICATION forming part of Design No. 25,315, dated March 31, 1896.

Application filed February 13, 1896. Serial No. 579,179. Term of patent 7 years.

To all whom it may concern:

Be it known that I, WILLIAM A. MATHEWS, a citizen of the United States, residing at Gratis, in the county of Preble and State of Ohio, have invented and produced a new and original Design for a Body or Back for a Pocket Pencil-Case; and I do hereby declare the following to be a full, clear, and exact description of the invention, such as will enable others skilled in the art to which it appertains to make and use the same.

In the accompanying drawings, which represent a body or back for a pocket pencil-case embodying my design, Figure 1 is a perspective view; and Fig. 2 is a section through the case, taken on the line 2 2 of Fig. 1.

My design consists, essentially, of a body or back for a pocket pencil-case, the same being of a generally-rectangular shape and of greater length than width, having one end turned up forming a curved flange, and being corrugated with straight parallel corrugations from said curved flange to within a short

distance of the opposite end of said body where the said corrugations merge into a flat portion, and said body having a recess in each side, as shown in the accompanying drawings.

In Fig. 1, A indicates the flat portion of the body of the pencil-case, B indicates the corrugations, C indicates the curved flange, and D D indicate the recesses in the sides of the body. The upper corners of the case and the corners of the curved flange are shown rounded. The body of the case is thin and the corrugations are seen on both faces thereof, as shown in the sectional view, Fig. 2.

What I claim is—

The design for a body or back for a pocket pencil-case, substantially as herein shown and described.

In testimony whereof I affix my signature in presence of two witnesses.

W. A. MATHEWS.

Witnesses:

JOHN C. WILSON,
JOHN H. HOLT.
